(57) **CLAIM**

The ornamental design for a lip balm holder as shown.

DESCRIPTION

FIG. 1 is a PERSPECTIVE view of a lip balm holder showing my new design, wherein an environmental lip balm is inserted in the holder;

FIG. 2 is a PERSPECTIVE view thereof;

FIG. 3 is a SIDE elevational view thereof;

FIG. 4 is a SIDE elevational view thereof;

FIG. 5 is a SIDE elevational view thereof;

FIG. 6 is a BOTTOM elevational view, thereof; and,

FIG. 7 is a TOP elevational view, thereof.

Any broken line illustration of the environmental structure in the drawing is not part of the design sought to be patented.
